United States Patent Office

Des. 186,946
Patented Dec. 29, 1959

186,946

RELIGIOUS CROSS

Luther A. Schuessler, Chicago, Ill.

Application February 27, 1958, Serial No. 49,834

Term of patent 14 years

(Cl. D29—23)

Fig. 4.

Fig. 2 is a side view thereof taken from the right of Fig. 1;

Fig. 3 is a top view thereof; and

Fig. 4 is a front perspective view thereof.

I claim:

The ornamental design for a religious cross, substantially as shown.
